UNITED STATES PATENT OFFICE.

JOSEPH H. JACOBS, OF DENVER, COLORADO, ASSIGNOR TO THE JACOBS SPECIALTIES MANUFACTURING COMPANY, A CORPORATION OF COLORADO.

COMBINATION-PRESS.

1,326,511.

Specification of Letters Patent. Patented Dec. 30, 1919.

Application filed February 5, 1918. Serial No. 215,522.

To all whom it may concern:

Be it known that I, JOSEPH H. JACOBS, citizen of the United States, residing in the city and county of Denver and State 5 of Colorado, have invented certain new and useful Improvements in Combination-Presses; and I do declare the following to be a full, clear, and exact description of the invention, such as will enable others skilled 10 in the art to which it appertains to make and use the same, reference being had to the accompanying drawings, and to the characters of reference marked thereon, which form a part of this specification.

15 My invention relates to a press adapted for use in machine shops in various relations, as in the use of dies. In other words, it is well adapted to perform the function of a die press, but it may be used in many other 20 relations where a similar or analogous function is required.

My improvement consists of a frame work having two spaced parallel bars upon which is slidably mounted a support for the article 25 to be acted on by the press, this support being normally locked in the desired position of adjustment through the medium of dogs engaging ratchet teeth with which the bars are provided. By releasing these dogs the 30 said member may be quickly adjusted vertically through the medium of a rack and pinion construction, racks being formed on the said bars and the pinions being mounted on the adjustable member and connected 35 to coöperate.

The other member of the device carries a divided nut which is normally spring held in coöperative relation with a screw which may carry a tool of any desired character, 40 as a die, for punching or embossing. The two parts of the nut are adjustable to disengage them from the screw, in which event the latter may be quickly adjusted vertically 45 through the medium of a shaft and pinion, the latter coöoperating with the screwthreads and having its periphery grooved and recessed to engage said threads.

Having briefly outlined my improvement, I will proceed to describe the same in detail, 50 reference being made to the accompanying drawing in which is illustrated an embodiment thereof. In this drawing:

Figure 1 is an elevation of my improved press shown in the upright position.

55 Fig. 2 is a cross section taken on the line

2—2, Figs. 1 and 2, looking downwardly, the parts being shown on a larger scale than in Fig. 1, but on the same scale as Fig. 3.

Fig. 3 is a fragmentary side elevation of the structure viewed as in Fig. 1, but showing the parts on a larger scale. Also this is a view looking in the direction of the arrows 3—3, Fig. 2.

Fig. 4 is a section taken on the line 4—4, Fig. 2 viewed in the direction of the arrows. 60

Fig. 5 is a section taken on the line 5—5, Fig. 1, viewed in the direction of arrows 5.

Fig. 6 is an elevation of the device looking in the direction of arrows 6, Fig. 1, the device in another position being indicated by 70 dotted lines and partly broken away.

Fig. 7 is a section taken on the line 7—7, Fig. 5.

Fig. 8 is a section taken on the line 8—8, Fig. 1, looking toward the right. 75

Fig. 9 is a perspective view illustrating the feature of construction employed for controlling the ratchet and dog mechanism, the parts being shown on a larger scale than in the other views. 80

The same reference characters indicate the same parts in all the views.

Let the numeral 5 designate a frame composed of two spaced parallel side members 6 which are centrally provided with longitudinally disposed toothed or cogged racks 7, these racks being formed directly on parallel parts 8 which are secured in any suitable manner to the parts 9 of the members 6, the latter being connected at the top by an arch 90 10, the arch and parts 9 being preferably formed of standard channel iron, usually found in stock. The parts 8 upon which are formed the racks 7 are of different metal and are secured to the members 9 so that so far as 95 the operation of the structure is concerned the two parts or members are substantially integral. The parts 8 are connected at their extremities which are upmost when the structure is in the upright position, as shown in 100 full lines of the drawing, by a transverse member 12 perforated, as shown at 13, to receive a screw 14 which is grooved on opposite sides to receive dogs 15 which are secured to the part 12, as shown at 16. These dogs prevent the screw from turning when the device 105 is in use.

Mounted on the transverse member 12 and arranged above the same (assuming that the device is in the upright position) is a block 110

17, in which is mounted a divided nut 18 composed of two parts 19 which are spring actuated to normally engage the threads of the screw 14 in coöperative relation but are 5 movable away from the screw when it is desired to adjust the latter without turning the nut. In the drawing, the nut is mounted in a cavity 20 of the block, this cavity being normally closed by a cover 21 held in place 10 by screws 22. Each nut member 19 is provided with a laterally extending arm or stem 23 which passes through an end perforation 24 in the block beyond the said cavity. The stems 23 are surrounded by spiral springs 15 25 whose opposite extremities respectively engage the end surfaces 26 of the block beyond the cavity 20 and collars 27 fast on the stems 23. Arranged above the cover 21 are two laterally slidable members 28 carrying anti-frictional rollers 29 at their inner extremities, their outer portions passing through guides 30. Each of these parts 28 is provided with a depending lug 31 which passes through a slot formed in the top plate 21 and bears against the collar 27. Mounted 25 above the top plate 21 and coöperating with the anti-frictional rollers 29 of the parts 28 is a cam member 32 which is journaled to rotate on a sleeve 33 which is secured to the top of the arch 10 at its upper extremity and to the top plate 21 at its opposite extremity. As this cam member is actuated by imparting partial rotation thereto on the sleeve 33, it will act on the parts 28 to force 30 them outwardly, and by virtue of the depending lugs of the parts 28, the nut members 31 will be separated by virtue of the construction heretofore explained, the cam member being provided with arms 34 for 35 convenience of manipulation. As soon as the nut members are actuated to release them from engagement with the screw 14, this screw may be vertically adjusted through the medium of a shaft 35 upon which is 40 mounted and made fast a pinion 36 whose periphery is fashioned to engage the threads of the screw in coöperative relation, whereby the screw may be quickly raised and lowered. When it is desired to exert much 45 power through the medium of the screw, the nut members will engage the latter in coöperative relation and the block 17 will be rotated on the screw which is locked against rotation. Hence, as the block is actuated 50 in the manner stated, the screw will be adjusted vertically in the usual way. The block is equipped with a hand wheel 37 for convenience of manipulation.

The opposing member of the press is arranged below the member 17, the term "below" being used with reference to the parts when the frame member 5 is in the upright position though when the structure is in the position indicated by dotted lines in 55 Fig. 6 both of the members will be at the

same height, since the parts 9 of the frame upon which the two members are mounted will be in the horizontal instead of the vertical position. The second or opposing member will be designated in its entirety by the 70 numeral 38 and is adjustable on the parts 9 of the frame to move either toward or away from the member 17. This member 38 is of channel shape, as illustrated in the drawing, and is provided at its opposite ends with 75 clamping parts 39 which are connected by bolts 40 which pass through perforations formed in the channel member 38 and the parts 39, nuts 41 being used to secure the clamping parts in place. These parts 39 80 turn inwardly at their outer extremities, as shown at 42, whereby they engage the outer edges of the channel flanges of the parts 9 of the frame. The bolts 40 also pass through cylindrical parts 43 of dogs 44 which are 85 journaled on the bolts, the said dogs being equipped with teeth or projections 45 which are adapted to engage ratchet teeth 46 which are formed on the parts 9 of the frame, these ratchet teeth being arranged on opposite sides of centrally located toothed racks 7, the dogs being centrally recessed, as shown at 48, to make room for the toothed racks, whereby the dogs are free to move sufficiently to throw their projections into and 90 out of engagement with the ratchet teeth without the interference of said racks. The dogs are adjustable for the purpose of releasing the member 38 from its locked relation upon the frame through the medium of 95 a rod 49 which is arranged within the chamber of the channel and connected at one extremity, as shown at 50, with a projection 51 formed on the cylindrical part of the dog, while its opposite extremity is connected, as shown at 52, with a similar projection 53 formed on the cylindrical part of the opposite dog, the two projections, as shown in the drawing, being oppositely disposed on the two dogs with reference to their axes, 100 whereby the movement of the rod in one direction or the other imparts corresponding movement to both dogs, whereby the projections of the two dogs are thrown simultaneously out of engagement with the ratchet 105 teeth of the frame. The rod 49 is actuated to perform the last named function through the medium of an arm 54 which is secured to a spindle 55 journaled in the two flanges of the channel shaped member 38, the said 110 spindle having a depending crank arm 56 slotted, as shown at 57, to receive the rod. The teeth or projections 45 of the dogs are normally held in engagement with the ratchet teeth of the frame by a torsional 115 spring 58 surrounding the spindle, but having one extremity secured thereto, as shown at 59, while its opposite extremity is secured to the channel member 38, as shown at 60. The torsional stress of this spring upon the 120

130

spindle actuates the crank arm 56 to cause the latter to engage a stop 61 formed on the rod, the crank arm, as illustrated in the drawing, engaging the rod between the stop 5 61 and a second stop 62.

When the dogs are disengaged from the ratchet teeth of the frame, the member 38 is adjusted longitudinally of the frame by means of pinions 63 which engage the racks 10 7 of the frame. As illustrated in the drawing one of these pinions is mounted on a spindle 64 journaled in one extremity of the member 37 and the adjacent clamping parts 39 of the structure, the spindle 64 15 having an extension at one end which is fashioned, as shown at 65, to receive a socket wrench which may be of the brace and bit type, whereby the spindle, together with its pinion, may be rotated in coöperative relation 20 with the rack. In order that this movement of the spindle 64 may impart a corresponding movement to the pinion 63 on the opposite side, the last named pinion is mounted on a spindle 66 which also carries 25 a bevel-gear 67 meshing with a similar gear 68 fast on one extremity of a longitudinally disposed shaft 69 whose opposite extremity is equipped with a gear 70 meshing with a similar gear 71 fast on the spindle 64. By 30 virtue of this construction the two pinions 63 are simultaneously actuated to impart longitudinal travel to the member 38 on the frame whether the latter is in the horizontal or vertical position. When the frame is in 35 the upright position it will only be necessary to actuate the lever arm 54 in the proper direction to release the dogs from the ratchet teeth of the frame in order to allow the member 38 to move downwardly or horizontally 40 of the frame parts 9; while the member 38 may be moved in the opposite direction through the medium of the pinions and racks, a suitable socket wrench of the brace and bit type being employed to actuate the spindles through the coöperation of 45 the shaft 69 which is geared to the spindles of the pinions as heretofore explained. It is evident that by the manipulation of the spindles the transverse member 38 may be 50 moved in either direction according to the rotation of the spindles, when the dogs are in the disengaged position or when their projections 45 are out of engagement with the ratchet teeth 46.

55 The transverse member 38 is centrally provided with a perforation 72 adapted to receive an article which may be of such character as to be vertically positioned in order that it may be acted on in the endwise direction by the screw 14 or by a tool of any desired character connected with the lower extremity of said screw. This article may be a shaft or rod from which pulleys are to be pressed, in which case a die for 60 65 the purpose would be secured to the lower

end of screw shaft 14, as by means of a set screw 100 running into a socket (not shown) in the lower end of screw shaft 14. In order that the article may be properly positioned within the opening 72 I have provided a slot 70 or side opening 73 which is normally closed by a reinforcing plate 74. This plate is provided with a bottom flange 75 which extends underneath one of the flanges of the channeled member 38, and this flange is perforated at one end to receive a fastening screw 76 which forms a pivot upon which the plate may be swung into and out of position, while the flange at its opposite end is slotted, as shown at 79, to engage another 80 screw 80 which is threaded into the adjacent flange of the member 38. In order to properly hold the plate 74 in the assembled relation with the body of the transverse member, I employ two screws 81 which pass 85 through perforations in the plate of sufficient size to allow the screw heads to pass through. I then insert spring washers 82 between the screw heads and the plate, whereby the latter is under tension to maintain its proper position in close contact with the body member. In order to hold the spring washers in proper position they are slotted on one side to receive pins 83 which are fast in the plate a short distance from 90 the screws. These pins prevent the washers from rotation on the screws and possible disengagement, while at the same time the washers are readily removable whenever it becomes necessary to swing the plate away 95 from the body member.

In order to facilitate the rotary movement of the block 17, I provide a circular bearing consisting of a wire or small rod 84 which is partly embedded in a groove formed in 100 the upper surface of the frame part 12, but extends sufficiently above the part 12 to form a bearing for the block which may be provided with a circular groove which the bearing also engages. This bearing ring 84 110 slightly spaces the block from the frame part 38 and reduces the friction incident to the rotation of the block to a minimum.

The extremity 10 of the frame which is uppermost when the structure is in the upright position, is provided with a swinging member 85 which is pivotally connected with the frame, as shown at 86. When it is desired to use the machine in the horizontal position or that illustrated by dotted lines 115 in Fig. 6, the frame is moved to the horizontal position, in which event the base 87 upon which the structure is supported in the upright position, forms a support for one end 120 of the structure, while the swinging member 85 assumes the vertical position and forms a support for the opposite extremity 125 of the structure. In this event, one end of the base 87 may have a plate 88 which is bolted to a stationary support or surface, 130

as shown at 89, and hinged to the adjacent extremity of the base 87, as shown at 90, so that when the device is moved to the horizontal position, it will simply turn on the hinge 90, while the plate 88 will remain in its normal position. By virtue of this construction the press is locked against displacement upon the floor or bench, or other surface or supporting structure where it is employed.

From the foregoing description, the use and operation of my improved press will be readily understood. The screw 14 may be moved longitudinally on the frame either by rotating the block 17 when its sectional nut is in coöperative engagement with the screw, or the nut members may be disengaged from the screw, in which event the latter may be given its endwise or longitudinal movement through the instrumentalities of the shaft 35 and the pinion 36. Again, in order to move the member 38 longitudinally of the frame to coöperate with the screw 14, it is only necessary to disengage the dogs 44 from the ratchet teeth of the frame to permit the member 38 to be moved in either direction thereon, the dogs automatically assuming their locking relation with the ratchet teeth as soon as they are released from the disengaging stress through the medium of the stress exerted in the opposite direction by the torsional spring 38 mounted on the spindle 55, as heretofore explained.

Having thus described my invention, what I claim is:

1. A combination press comprising a frame, a rotary block mounted on the frame, a screw passing through an opening in the frame, a divided nut mounted on the block and normally spring held in coöperative relation with the screw, means for adjusting the nut to disengage it from the screw, and means for imparting longitudinal movement to the screw when disengaged.

2. A combination press comprising a frame, a rotary block mounted on the frame, a screw passing through an opening in the frame, a divided nut mounted on the block and normally spring held in coöperative relation with the screw, means for adjusting the nut to disengage it from the screw, means for imparting longitudinal movement to the screw when disengaged, said means comprising a shaft journaled in the frame, and a pinion mounted on the shaft and engaging the screw.

3. A press comprising a frame, a rotary block mounted thereon, a screw passing through an opening in the frame, a divided nut mounted on the block and normally spring held in coöperative engagement with the screw, and means for adjusting the nut to disengage it from the screw, said means including a cam mounted to rotate and arms

acted on by the cam and having parts engaging the nut members and arranged to move the latter against the normally acting spring tension.

4. A press of the class described comprising a frame, a block mounted to rotate thereon, a screw passing through an opening in the frame, a divided nut mounted on the block and normally spring held in coöperative engagement with the screw, means mounted on the frame and engaging the screw to lock the latter against rotary movement, means for adjusting the nut to disengage it from the screw, and means for imparting movement to the screw in the direction of its axis when the nut is disengaged therefrom.

5. The combination with a frame member having spaced parallel arms, a screw movable in the direction of its axis on the frame member, an opposing member movably mounted on the frame member, means for adjusting the opposing member on the arms of the frame member comprising dogs mounted on one member and a coöperating ratchet carried by the other member, means for connecting the dogs, and means attached to the connecting means for simultaneously actuating the dogs.

6. The combination of a frame having spaced arms and a transverse connecting member, a screw endwise adjustable on the transverse member of the frame, an opposing member movable on said arms of the frame and having dogs coöperating with ratchet teeth formed on the arms, a rod connecting the dogs, a spindle journaled in the opposing member and connected with the rod, a torsionally acting spring mounted on the spindle to normally hold the dogs in engagement with the ratchet teeth of the arms, and a corresponding arm mounted on the spindle for hand manipulation.

7. The combination with a frame, of a screw locked against rotary movement, a nut coöperating with the screw, means for releasing the nut from the screw, and means for imparting endwise movement to the screw when disengaged from the nut.

8. The combination with a frame, of a screw locked against rotary movement, a nut coöperating with the screw, means for releasing the nut from the screw, means for imparting endwise movement to the screw when disengaged from the nut, an opposing member movably mounted on the frame, and means for adjusting said member comprising ratchet and dog mechanism and rack and pinion devices.

9. The combination with a frame, of a screw movable on the frame in the direction of the axis of the screw, means for actuating the screw, an opposing member arranged to coöperate with the screw, the opposing member being movably mounted on the frame,

and means for actuating said member, comprising ratchet and pawl mechanism and rack and pinion devices, the ratchet being located at the side of the rack.

- 5 10. The combination with a frame, of a screw movable on the frame in the direction of the axis of the screw, means for actuating the screw, an opposing member arranged to coöperate with the screw, the opposing

member being movably mounted on the frame, and means for actuating said member, comprising ratchet and pawl mechanism and rack and pinion devices, the ratchet being located at opposite sides of the rack and the pawl being recessed to pass over the 15 rack.

In testimony whereof I affix my signature.
JOSEPH H. JACOBS.
